UNITED STATES PATENT OFFICE.

LEE HALL, OF ST. PAUL, MINNESOTA.

REFRIGERATOR.

No. 562,824.

Specification of Letters Patent. Patented March 24, 1908.

Application filed September 17, 1906. Serial No. 334,849.

To all whom it may concern:

Be it known that I, LEE HALL, a citizen of the United States, residing at St. Paul, in the county of Ramsey and State of Minnesota, have invented certain new and useful Improvements in Refrigerators, of which the following is a specification.

My invention relates to improvements in refrigerators, its object being to provide an air tight refrigerator conveniently constructed for receiving, carrying and preserving game and other perishable articles.

To this end the invention consists in the construction, combination and arrangement of parts hereinafter described and claimed.

In the accompanying drawings forming part of this specification, Figure 1 is a perspective view of the refrigerator shown partly broken away. Fig. 2 is a vertical section on line $w-w$ of Fig. 1; Fig. 3 is a transverse section on line $x-x$ of Fig. 2, and Fig. 4 is a vertical section through the sealing plug and cover on line $z-z$ of Fig. 1, and through the vent-hole, showing the coöperation of the parts when the cover is closed.

In the drawings A represents the outer receptacle of the refrigerator, and 2 its hinged cover. Centrally arranged within the receptacle is an open topped provision box B having end walls 3 and side walls 4 spaced apart from the end and side walls, respectively, of the outer receptacle a sufficient distance to permit the free circulation of water 5 between the walls of the receptacle and the provision box. The end walls of the provision box are also spaced a sufficient distance from the respective end walls of the receptacle to leave between them chambers C large enough to contain lumps of ice. These chambers are provided with hinged covers 6, having frictional engagement with the ears or beads 7 upon the upper ends of the telescoping bell 8. The provision box is secured at the bottom of the receptacle in any suitable way to keep it from displacement by the surrounding water when the bell is lifted. This may be done, as shown in the drawings, by having the walls of the provision box integral with, or secured to, the bottom of the receptacle so as to form therewith a water tight joint, the bottom of the receptacle thus becoming the bottom of the provision box.

The telescoping bell 8 is constructed to fit loosely over the provision box B, so as to leave space enough between its walls and the walls of the provision box for the circulation

of water. The top 9 of the bell is formed at the sides with flanges 10 adapted to engage and rest upon the beads or flanges 11 on the inside of the side walls of the outer receptacle. When the bell is so supported its top will be held up out of contact with the upper ends of the provision box walls, and the lower ends of its walls out of contact with the bottom of the receptacle. Thus the water in the outer receptacle is free to pass under the walls of the bell and up between them and the walls of the provision box, thus sealing passage from the provision box at the bottom. And by leaving a space between the top of the bell and the upper ends of the provision box walls, the odors and gases of the provisions can reach the water and be absorbed by it.

To prevent the water from being drawn up into the provision box when the bell is raised, the top of the box is formed with a vent-hole 12 having an upwardly extending wall 13. To seal the vent-hole when the cover 2 of the receptacle is closed, a plug 14 is elastically supported upon the inside of the cover in position to engage the annular wall 13 and stop the vent when the cover is closed. As shown in the drawings the plug is carried by a spring strip 15 having its ends slidingly supported in guides 16 secured upon the cover.

In use, the game or provisions are placed in the provision box and the bell telescoped over the top of the box. The chambers C are then filled with water to any desired height above the lower ends of the walls of the bell, and also with any desired amount of ice. The water will circulate all around between the side walls of the box and the receptacle and will rise between the walls of the box and bell to the same height as in the chambers C. When the cover 2 is closed, it will force the plug 14 into vent-closing engagement with the vent-wall 13. Thus the water at the bottom and the plug at the top form together an air tight seal for the provision box.

Modifications may be made in the details of construction without departing from the spirit of the invention the scope of which is defined in the claims.

I claim:

1. A refrigerator comprising an outer receptacle and a cover therefor, an open-topped provision box arranged within the receptacle, a bell telescoping over the box and formed in its top with a vent hole, and an

elastically supported plug adapted to be thrust by the cover into vent-sealing position.

2. A refrigerator comprising a receptacle and its cover, an open topped provision box arranged within the receptacle and having its walls spaced apart from the walls thereof, a telescoping bell fitting loosely over the box, the top of the bell being formed with a vent-hole, and means carried upon the inside of the cover for stopping the vent-hole when the cover is closed.

3. A refrigerator comprising a receptacle and its cover, an open topped provision box arranged within the receptacle and having its walls spaced apart from the walls of the receptacle, a telescoping bell fitting loosely over the box, the top of the bell being formed with a vent-hole, and a plug elastically supported upon the inside of the cover in position to stop the vent-hole when the cover is closed.

4. A refrigerator comprising an outer receptacle and a cover therefor, an open-topped provision box within the receptacle, a bell telescoping over the box, an ice chamber arranged between the bell and the wall of the receptacle, and a cover for the ice chamber having frictional engagement with the bell to secure it against accidental opening.

5. A refrigerator comprising an outer receptacle and a cover therefor, an open-topped provision box within the receptacle, a bell telescoping over the box, an ice chamber arranged between the bell and the wall of the receptacle, an ear at the upper end of the bell, and a cover hinged to the wall of the receptacle and having frictional engagement with the ear whereby it is secured against accidental opening.

6. A refrigerator comprising an outer receptacle and a cover therefor, an open topped provision box within the receptacle, a bell telescoping over the box and supported upon

the receptacle with its top out of contact with the box and its walls extending down nearly to, but held out of contact with, the bottom of the receptacle, the walls of the bell and the receptacle being spaced apart to form an ice chamber, and a cover for the ice chamber independent of the cover for the receptacle.

7. A refrigerator comprising an outer receptacle formed with a bead upon the inside of each of its side walls, an open topped provision box arranged within the receptacle, a bell telescoping over the box and formed at the top with side flanges to rest upon the beads of the receptacle so as to hold the bell in suspended position out of contact with the provision box, the walls of the bell extending down nearly to the bottom of the receptacle, an ice chamber arranged between the walls of the bell and receptacle, a cover for the receptacle and an independent cover for the ice chamber.

8. A refrigerator comprising an outer receptacle and a cover therefor, the receptacle being formed upon its side walls with interior beads, a telescoping bell fitting loosely over the provision box, and formed with side flanges at the top to overlap and rest upon the beads of the receptacle so as to hold the bell in suspended position and close the space between the bell and the receptacle, an ice chamber arranged at each end of the bell, and a cover for each chamber hinged to the adjacent end of the receptacle, said cover being constructed to overlap the beads on the sides of the receptacle and also to overlap and interlock with the adjacent end of the bell.

In testimony whereof I affix my signature in presence of two witnesses.

LEE HALL.
